UNITED STATES PATENT OFFICE.

JAMES R. SMITH, OF MECHANICSVILLE, NEW YORK.

FLANGE FOR DRAINS, VENTS, AND OTHER PURPOSES.

1,150,231.

Specification of Letters Patent. Patented Aug. 17, 1915.

Application filed November 5, 1914. Serial No. 870,538.

To all whom it may concern:

Be it known that I, JAMES R. SMITH, a citizen of the United States, residing at Mechanicsville, county of Saratoga, and State of New York, have invented certain new and useful Improvements in Flanges for Drains, Vents, and other Purposes, of which the following is a specification.

This invention relates to roof flanges for drains, vents and other purposes.

My object is to provide a roof flange which will be adapted for use in connection with either a wooden or a concrete roof and will embody improvements whereby the joint between the conductor or pipe and the flange and roof will be water-tight, secure and rigid, and easily installed, repaired or removed.

The invention is adapted for use in connection with any pipe or conductor on either a concrete or a wooden roof and in connection with a drain pipe or vent pipe, and whether or not a cap be used, while being adapted for the removal of the cap if one is employed.

I am aware that the invention is susceptible of modification within the spirit and scope thereof, but in the following description have set forth one embodiment thereof and illustrated the manner in which the flange is connected to both a wooden and a concrete roof.

The novel features and points of the invention are recited in the appended claims.

35 In the accompanying drawings: Figure 1 is a vertical section showing the invention applied to a concrete roof; and Fig. 2, a similar view showing it in position on a wooden roof.

40 Referring first to Fig. 1, the concrete roof appears at 1 and the wooden form for constructing the roof at 2. The flange proper is made as a single, integral casting having the cup 3 provided with opening 4 in its bottom, and the annular concentric flanges 5 and 6 having the base 7 and out-standing flange 8. The flanges 5 and 6 define an open topped annular channel which surrounds the upper part of the cup 3. The flange 8 is

45 embedded in the concrete 1, while the flange or wall 6 constitutes the inner abutment or boundary for the concrete 1, and the bottom 7 rests upon the concrete roof 1. Preferably, the interior of the cup 3 tapers from its upper margin 9 to its bottom 10 so that the jute packing 11 and the calking lead or

material 12 may be tightly driven or tamped into the cup and around the pipe or conductor 13. The opening 4 is circular and the bottom 10 of the cup snugly receives the pipe 60 or conductor 13 so that when the jute 11 and calking lead 12 are packed or tamped down, a water-tight and rigid joint is formed between the cup and the pipe.

The felt or slag roofing 14 which lies on 65 the upper surface of the concrete roof 1 is brought down into the annular pit or well and against the flange or wall, as shown at 15, and lies on the bottom 7, within said pit or well, as at 16, the parts 15 and 16 extending 70 all the way around the pit or well so as to pack every part of the joint. An annular spring locking ring 17 lies in the well or pit and expands against the part connecting the parts 15 and 16 so as to hold the slag 75 or felt roofing 14 against the wall 6 and bottom 7. The ring 17 may be of any preferred form such as a split expansion ring. Thereafter tar 18 is run into the well or pit on top of and against the felt or slag roofing 80 14, thus completely sealing the joint between the flange 6 and the roof. I wish it understood that when I refer to a felt or slag roofing 14, I have also reference to any material which may be superposed on the roof 85 1 and brought down into the well or pit for the purpose of sealing the joint. Furthermore, when I refer to tar 18, I also am understood as including any packing or filling, preferably one of a plastic nature which 90 will harden on cooling, that may be used for this purpose.

If the flange is employed at the upper end of a drain pipe or conductor 13, a dome shaped perforated cap 19 may be provided, 95 which will have lugs or ears 20 to fit in the upper part of the cup 3 above the calking lead 12 so as to be readily placed in position or removed and for the purpose of excluding foreign matter. If, however, the invention is used in connection with a vent pipe, as shown by dotted lines 21, Fig. 1, the cap 19 will be dispensed with, as vent pipes run up above the roofing.

Referring to Fig. 2, I have there shown 105 the invention as applied to a wooden roof 22. With such a roof, it is unnecessary for the roof to extend up against the side of the cup 3. The flange 8 in this form of the invention, instead of being provided as an 110 extension in the same general plane as the bottom 7, is used as a supporting flange 8a

at the upper end of the wall 6 and rests upon and is preferably sunk flush with the top of the roof 22. Otherwise the construction is as previously described and in this 5 form of the invention, the pipe or conductor 13 may be a drain or be extended above the roof as a vent pipe, as shown by dotted lines 21, Fig. 1. In both forms of the invention, the flanges 8, 8^a, serve as a support for the 10 casting, the flange 8 being embedded in the concrete in Fig. 1, but it will be understood that the said flange 8 could be provided at the top of the flange or wall 6 in connection with a concrete roof.

15 Having thus described my invention, what I claim as new and desire to secure by Letters Patent, is:—

1. In a roof flange for pipes or conductors, a centrally disposed cup adapted to receive the pipe or conductor, a bottom wall 20 outstanding from, and joined to the cup, a side wall joined to the bottom wall and arranged concentric to the cup and defining, in connection therewith, an annular well or 25 pit for the reception of packing for the joint between the roof flange and the roof, and a flange projecting outwardly from the side wall and adapted for supporting the entire device from the roof.

30 2. The combination with a roof, of a centrally disposed cup, a pipe or conductor received in said cup, packing contained within the cup and adapted for packing the joint 35 between the pipe and cup, a bottom wall outstanding from, and joined to, the cup, a

side wall joined to the bottom wall and arranged concentric to the cup and defining, in connection therewith, an annular well or pit, a flange projecting outwardly from the side wall and engaged with the roof for supporting the device therefrom, a roof covering received in the well or pit, and a packing in said well or pit which packs the joint of the roof covering therewith. 40

3. The combination with a roof, of a centrally disposed cup, a pipe or conductor received in said cup, packing contained within the cup and adapted for packing the joint between the pipe and cup, a bottom wall 45 outstanding from, and joined to, the cup, a side wall joined to the bottom wall and arranged concentric to the cup and defining, in connection therewith, an annular well or pit, a flange projecting outwardly from the side wall and engaged with the roof for supporting the device therefrom, a roof covering received in the well or pit and lying 50 against the side and bottom wall aforesaid, a holding or securing ring contained within the well or pit for pressing the roof covering against the bottom and side walls aforesaid, and a packing in said well or pit which 55 packs the joint of the roof covering therewith. 60

In testimony whereof, I hereunto affix my 65 signature in presence of two witnesses.

JAMES R. SMITH.
